IGNITING MEANS FOR BURNERS

Don Beggs, Toledo, Ohio, assignor, by mesne assignments, to Surface Combustion Corporation, Toledo, Ohio, a corporation of Ohio

Application April 1, 1941, Serial No. 386,236

7 Claims. (Cl. 126—91)

This invention relates to improvements in heating apparatus of the type wherein fuel gas and combustion-supported air are delivered to a combustion chamber in separate but contiguous streams in order to obtain delayed combustion. One example of such apparatus is shown in patent to Hepburn et al., No. 2,047,471, wherein the combustion chamber is a tube adapted to be used as a heating element in furnace chambers and the like. It will also be noted that in this patent the means for igniting the gas comprises a premix burner around the discharge end of the fuel supply tube. The object of the present invention is to provide a simple and practical improvement in means for providing a pilot flame for a firing system of the type disclosed in said patent. Other objects will appear as the description proceeds.

In the accompanying drawing wherein the preferred form of the invention is disclosed—

Fig. 1 illustrates the type of heating apparatus with which the invention has special utility; namely, heating apparatus, embodying an internally fired tube for use as a heating element in furnace chambers and the like.

Fig. 2 is an enlarged view of the firing end of the radiator tube with parts broken away to more clearly show the improvement.

Fig. 3 is a cross section on line 3—3 of Fig. 2.

Fig. 4 shows a slight modification of the invention disclosed in Fig. 2.

Fig. 5 shows the application of the invention to a form of burner somewhat different from that shown in Fig. 2.

Fig. 6 is a cross section on line 6—6 of Fig. 5.

Fig. 7 is a cross section on line 7—7 of Fig. 6, for the purpose of illustrating the application of the modification shown in Fig. 4.

In Fig. 1, 10 indicates a furnace chamber wall and 11 a heating tube which extends into and out of said chamber through said wall. At one end of said tube is a suction producing device 12 for producing draft through the tube. Projecting into the other end of the tube to a point some distance inwardly from the air intake end 13 thereof is a fuel supply tube or conduit 14, it being understood that the air for supporting combustion of the fuel enters the tube 11 through the annular flow passage 15 about the gas supply conduit.

The present invention is predicated on the phenomenon that a zone of reduced pressure or partial vacuum tends to occur at the downstream side of a non-streamline body placed in the path of flow of a stream of air or other gas. In the present invention I take advantage of this phe-

nomenon in the following way: Referring to Figs. 2 and 3, 16 indicates a relatively small baffle in the form of a radially extending finger at one end of a rod 17 positioned in the air passage 15, the finger being relatively close to the discharge end of the gas discharge tube 14. Due to the zone of reduced pressure at the downstream side of this finger or baffle 16 some of the gas flowing from the tube 14 will tend to flow toward the zone of reduced pressure and in so doing will become mixed with the air. This mixture on being ignited will form a pilot flame at the end of the fuel tube 14 in igniting proximity to the point where the main air and gas streams meet as will now be readily understood.

Other relatively small baffles 18 may extend radially outward from the tube 14 itself to provide a plurality of pilot flames around the tube. The primary reason for utilizing a rod 17 for supporting the baffle 16 is to permit the latter to be utilized as a spark electrode for igniting the mixture produced therebehind as said—it being understood that the rod 17 is connected to a suitable source of electric power (not shown). It will also be understood that once the air-gas mixtures behind the baffles 16 and 18 have been ignited the resulting pilot flames will tend to persist as long as both air and fuel gas flow into the radiator tube 11.

In Fig. 4, the arrangement is the same as in Fig. 2 except that I provide a relatively small gas port 19 in the wall of the gas tube at the downstream side of the baffle 18 for the more direct flow of the gas from the tube to the zone of reduced pressure.

In Figs. 5 and 7, I have shown how the invention may be applied to a modified form of burner adapted to fire into a furnace 20 such as a forge furnace. The gas passage is indicated at 21 and the air passage at 22, the two passages being separated by a partition wall 23. The primed numerals indicate parts similar to those indicated by the same but non-primed numerals in the other figures and the mode of operation will be readily understood from what has already been said.

From the foregoing description it can be readily seen that the present invention provides a relatively simple and practical improvement in means for proving a pilot flame for a gas burner of the type disclosed.

What I claim is:

1. The combination with an air passage and a gas passage separated from each other by a partition wall for delivering separate streams of fuel

gas and air to a combustion space, of means for turbulently intermixing relatively small quantities of said streams to produce a premix pilot flame at the end of said wall, said means comprising a relatively small baffle positioned in the air passage to cause a turbulent partial vacuum to be produced therein behind the baffle, said baffle being positioned in such close proximity to the end of said wall that the said partial vacuum will be effective to divert towards itself from the main gas stream enough gas to produce the air-gas mixture which supports the pilot flame, said baffle being spaced from said wall to provide a spark gap therebetween for igniting the air-gas mixture produced as said.

2. The combination with an air passage and a gas passage separated from each other by a partition wall for delivering separate streams of air and fuel gas to a combustion space, of means for producing a premix pilot flame in relatively close proximity to the downstream terminal of said wall for igniting the air and gas issuing from said passages, said means comprising a relatively small baffle in one of said passages in relatively close proximity to the downstream terminal of said wall for producing adjacent said terminal a turbulent partial vacuum to produce the air-gas mixture that maintains said premix flame, said baffle being spaced from said wall to provide a spark gap therebetween for igniting said mixture.

3. The combination with an air passage and a gas passage separated from each other by a partition wall for delivering separate streams of air and fuel gas to a combustion space, of means for producing a premix pilot flame in relatively close proximity to the downstream terminal of said wall for igniting the air and gas issuing from said passages, said means comprising a relatively small baffle in the air passage in relatively close proximity to the downstream terminal of said wall for producing adjacent said terminal a turbulent partial vacuum which will be effective to divert towards itself from the main gas stream enough gas to produce the air-gas mixture that maintains said pilot flame, said wall being apertured in relatively close proximity to said baffle at the downstream side of the latter for the flow of gas through said wall.

4. In combination, a relatively long combustion tube which at its intake end has an air entering passage and a gas entering passage separated from each other by a partition wall so that the air and gas will initially enter the tube as separate straight away streams and which tube at its exhaust end has a suction device for producing a draft through the tube, and means for producing a premix pilot flame in the tube for igniting the gas where it first comes in contact with air after leaving the gas passage comprising a relatively small baffle in the air passage in relatively close proximity to the downstream terminal of said wall for producing behind said baffle a turbulent partial vacuum effective to divert towards itself from the main gas stream enough gas to produce the air-gas mixture that maintains said pilot flame.

5. In combination, a relatively long combustion

tube having at its exhaust end a suction producing device so that combustion-supporting air and fuel gas introduced into the tube at the front end thereof will tend to be drawn through the tube, a gas conducting tube projecting centrally into the front end of the combustion tube to discharge fuel gas centrally thereinto and to form between the tubes an annular passage for the incoming air, and means for producing within the combustion tube a premix pilot flame for igniting the fuel gas issuing from the said gas conducting tube, said means comprising a radially extending finger in the air passage in relatively close proximity to the discharge end of said gas conducting tube to produce behind the finger a turbulent partial vacuum effective to divert towards itself from the stream of gas from the gas conducting tube enough gas to produce behind the finger a zone of combustible mixture sufficient to maintain said pilot flame at said zone.

6. In combination, a relatively long combustion tube having at its exhaust end a suction producing device so that combustion-supporting air and fuel gas introduced into the tube at the front end thereof will tend to be drawn through the tube, a gas conducting tube projecting centrally into the front end of the combustion tube to discharge fuel gas centrally thereinto and to form between the tubes an annular passage for the incoming air, and means for producing within the combustion tube a premix pilot flame for igniting the fuel gas issuing from the said gas conducting tube, said means comprising a radially extending finger in the air passage in relatively close proximity to the discharge end of said gas conducting tube to produce behind the finger a turbulent partial vacuum effective to divert towards itself from the stream of gas from the gas conducting tube enough gas to produce behind the finger a zone of combustible mixture sufficient to maintain said pilot flame at said zone, the said finger being radially spaced from the gas conducting tube to form a spark gap therebetween for igniting said mixture.

7. In combination, a relatively long combustion tube having at its exhaust end a suction producing device so that combustion-supporting air and fuel gas introduced into the tube at the front end thereof will tend to be drawn through the tube, a gas conducting tube projecting centrally into the front end of the combustion tube to discharge fuel gas centrally thereinto and to form between the tubes an annular passage for the incoming air, and means for producing within the combustion tube a plurality of premix pilot flames each adapted to ignite the fuel gas issuing from the gas conducting tube, said means comprising a circumferential row of radially-extending fingers in the air passage in relatively close proximity to the discharge end of the gas conducting tube to produce behind each finger a turbulent partial vacuum effective to divert towards itself from the stream of gas issuing from the said gas-conducting tube enough gas to form behind each finger a zone of combustible mixture sufficient to maintain a pilot flame at said zone.

DON BEGGS.
